UNITED STATES PATENT OFFICE.

FRITZ A. SCHULZ, OF CHICAGO, ILLINOIS; IDA SCHULZ ADMINISTRATRIX OF SAID
FRITZ A. SCHULZ, DECEASED.

BENCH-VISE.

1,096,395.

Specification of Letters Patent.

Patented May 12, 1914.

Application filed March 20, 1911, Serial No. 615,761. Renewed October 12, 1912. Serial No. 725,535.

To all whom it may concern:

Be it known that I, FRITZ A. SCHULZ, citizen of the United States, residing at Chicago, in the county of Cook and State of Illinois, have invented certain new and useful Improvements in Bench-Vises; and I do hereby declare the following to be a full, clear, and exact description of the invention, such as will enable others skilled in the art 10 to which it appertains to make and use the same.

This invention has for its object to provide a device for automatically engaging and disengaging a screw-shaft with and from 15 an internally-threaded member by means of which relative movement of said members longitudinally of the screw-shaft is effected.

The invention is particularly applicable 20 to bench-vises to which the same more particularly relates but may be capable of various other applications in tools and machinery.

The invention consists in the features of 25 construction and combinations of parts hereinafter fully described and claimed.

In the accompanying drawings illustrating 30 the invention: Figure —1— is a view in side elevation of a bench vise embodying my invention. Fig. —2— is a plan view of 35 the same. Fig. —3— is a vertical transverse section of the same on an enlarged scale on the line 3—3 of Figs. —1— and —6—. Fig. —4— is a central vertical longitudinal section 40 of a nut employed taken on the line 4—4 of Fig. —5—. Fig. —5— is a front elevation of the nut. Fig. —6— is a fragmentary central vertical longitudinal section 45 on an enlarged scale on the line 6—6 of Fig. —2—. Fig. —7— is a fragmentary detail vertical longitudinal section on the line 7—7 of Fig. —8—. Fig. —8— is a vertical transverse section on the line 8—8 of Fig. —1—. Fig. 9 is a fragmentary detail horizontal 50 section on the line 9—9 of Fig. —7—.

My invention has for its main object to 55 provide means actuated by rotation of a screw-shaft for automatically engaging the same with and disengaging the same from a coacting threaded member such as a nut or threaded sleeve so as to enable said screw shaft to be freely moved longitudinally relatively to said nut or sleeve in either direction when desired, and to quickly and positively engage the same therewith when de-

sired so that relative longitudinal movement of said members in one direction can be accomplished only by relative rotation thereof in one direction.

The invention is particularly adapted to 60 bench vises and my invention comprehends a vise equipped with the aforesaid mechanism and which embodies other improvements in devices of this character which will be particularly described and ascertained in 65 the following specification.

The vise shown in the accompanying drawings is intended to be mounted upon a work-bench so that the operating mechanism falls below the bench. To this end I 70 provide a member most conveniently cast which consists of the jaw 1 which may be said to constitute the fixed jaw of the vise and which is adapted to contact with the front edge of the bench 2 indicated in dotted lines in Fig. —1—, said jaw constituting the vertical flange of a box-like structure 3 rectangular in plan and cross section; the latter being provided at its upper end with a peripheral flange 4 meeting the flange 80 or jaw 1 at its forward end and which is adapted to contact with the lower face of the bench 2. The said member 3 is open at the top and at one side the latter being adapted to be partially closed by means of 85 a plate 5 which abuts against flanges 6 and 7 respectively, and is held in place by means of a bolt 8 spanning said member 3 and secured at its other end in the opposite side wall 9 thereof. In the latter there is a rectangular recess 10 formed by bulging said plate. Below the bottom plate of the member 3 there is formed a rectangular sleeve 12 in which the guide bar 13 carrying the movable jaw 14 of the vise is received and 90 guided. The said member 3 is provided with relatively wide end flanges 15 and 16 in which the said guide member 12 terminates and which constitute the end walls 95 of the member 3, the flange 15 being integral with the jaw 1. In the said end walls of said member 3 openings 17 are provided which are disposed in axial alinement with each other and through which the screw shaft 18 of the vise is adapted to pass freely, the said openings coinciding in diameter substantially with the greatest diameter of said shaft 18, that is, the diameter of the ridges of the threads thereof. The said screw shaft is rotatably secured at one end 100 110

to the jaw 14 by means of the ball-and-socket joint shown in Fig. —7—, the purpose of the latter being hereinafter more fully described. The lever arm 19 for rotating said shaft is secured to the latter in the usual and well-known manner. The said screw shaft 18 is adapted to be engaged by a rocking member or sleeve 20, the latter having two oppositely disposed internally threaded portions 21 disposed respectively beyond the respective ends of a central sleeve 22, the axis of which is angularly disposed relatively to the axis of the said threaded portion 21, the axis of the latter intersecting the axis of said sleeve midway between the ends thereof. Disposed upon diametrically opposite sides of said sleeve 22 are trunnions 23, the axis of which intersects the axis of said sleeve 22 at the point of intersection of the axis of the threaded portions 21 therewith. The said threaded portions 21 are threaded on their concave faces to fit the threads of the shaft 18, the latter being adapted to be engaged therewith or disengaged in accordance with the oscillation or rocking of said member 20 upon the axis of the trunnions 23. The position of the member 20 when engaging the threads of the shaft 18 is clearly shown in Fig. —6— and its position when the threads of the flanges 21 are disengaged from the threads of the shaft 18 is clearly shown in Fig. —4—. One of said threaded portions 21 is provided with a projection 24 from the forward face of which two projections 25 and 26 extend, the latter being parallel with each other and parallel with the axis of said threaded portions 21.

Mounted upon the screw shaft 18 and rotatable relatively thereto is a sleeve 27, the inner diameter of which is the same as that of the openings 17, the said sleeve being provided between its ends with an opening 28 through which a flat spring 29 projects, the latter bearing between its ends upon the ridges of the threads of said screw shaft 18 and being secured at one end to a projection 30 of said sleeve 27 as shown in Fig. —3—, the other end of said spring being free. Said sleeve is provided at the end thereof opposing one end of the member 20 (the latter being that carrying the projection 24 and its projections 25 and 26) with a segmental flange 31, the periphery of which is drawn on an arc of greater diameter than said sleeve and on an axis eccentric thereto. The said flange 31 is provided on its periphery with a segmental flange 32 extending toward the said projection 24 of the member 20 and between the said projections 25 and 26 thereof, said flange 32 being provided at its opposite ends with projections 33 and 34 adapted to engage the projection 26 to limit the rotation of said sleeve 27 relatively to said shaft 18 in both directions.

The said spring 29 serves to frictionally engage the said sleeve 27 with the shaft 18 so that rotation of the latter in either direction will rotate said sleeve 27 therewith until one of said stops 33 or 34 engages the projection 26 whereupon the shaft 18 may be further rotated in the same direction without further moving said sleeve. The movement of said screw shaft 18 to the right serves to cause the portion of the flange 32 lying nearest, radially, to the axis of the shaft 18 to bear upon the projection 25 to turn the member 20 on its pivot to the position shown in Fig. —6— while rotation of the shaft to the left serves to turn said sleeve 27 in a direction to cause the portion of the flange 32 farthest radially removed from the axis of the shaft 18 to bear upon the lower portion of the projection 26 and thus turn said member 20 on its axis to the position shown in Fig. —4— thus releasing the threads of the shaft 18 from engagement with the threads of the threaded portions 21 and permitting said shaft to be freely moved longitudinally relatively to said members 3 and 20 and relatively to the sleeve 27 as will be obvious. The latter bears at one end against the front wall of the member 3 which is coincident and integral with the jaw 1, its movement longitudinally of the shaft 18 in the other direction being limited by engagement with the projection 24 of said member 20 as will be obvious. It will be obvious from the foregoing that when said shaft 18 is turned in a direction to cause the threads thereof, if engaged, to draw the jaw 14 toward the jaw 1, the sleeve 27 will be primarily rotated in a direction to throw the threads of the portion 21 into engagement with the threads of the shaft 18 thus necessitating continued rotation of the shaft 18 in the same direction in order to engage objects between said jaws 1 and 14. In practice, before said shaft 18 is rotated in said direction it is primarily moved longitudinally relatively to the member 3 so as to bring the jaw 14 approximately into the desired position relatively to the jaw 1 to accommodate the work loosely therebetween. By then rotating the shaft to the right the threads of the same will become engaged with the threads of the member 20 and upon further rotation of said shaft 18 in the same direction the work will become firmly engaged between the jaws 1 and 14. When it is desired to release the work the rotation of the shaft 18 to the left will primarily cause the sleeve 27 to be rotated therewith thereby throwing the member 20 into the position shown in Fig. —4— thus almost instantly releasing the work from engagement between said jaws 1 and 14 and permitting the last-named jaw to be freely moved away from the jaw 1 to the desired extent without further rotating the shaft 18.

- The trunnions 23 of the member 20 are adapted to be journaled in openings in the plate 5, and the side wall 9 of the member 3 respectively, the former, when disposed in 5 position and secured by means of the bolt 8, serving to hold the member 20 against movement in all directions relatively to the member 3 as will be obvious. If it is desired to remove the member 20 for purposes 10 of repair the bolt 8 must first be extracted whereupon the plate 5 may be removed and thereupon by first withdrawing the shaft 18 from said member 20 the latter may obviously be removed.
- 15 In using vises it is frequently desired to dispose the opposing jaws thereof angularly to each other in order to enable the same to accommodate themselves to engagement of opposite faces of work to be operated upon 20 which may be disposed angularly to each other. I have, therefore, provided means in the present vise for either maintaining said jaws 1 and 14 parallel with each other or permitting them to assume positions angularly relatively to each other. This I accomplish by mounting upon one end of the member 13 a substantially cylindrical projection or head 35 having a vertical axis coincident with the vertical axis of the ball 36 upon the forward end portion of the screw shaft 18 which fits within a substantially spherical recess 37 in the jaw 14 and is held in place therein by means of the plate 38 having an annular flange 39 bearing 35 upon the said ball 36 at the portion thereof projecting from said recess 37. The opening bordered by the flange 39 is laterally elongated so as to permit said jaw 14 to oscillate upon the vertical axis of said ball 40 36. At its lower end said jaw 14 is provided with an enlargement 40 projecting from the forward face thereof and into the bottom of which a partially cylindrical recess is formed which is adapted to receive 45 the cylindrical end portion or head 35 of said member 13. The latter is provided with a horizontal opening adapted to register with horizontal openings in the side portions of the lower end of said jaw 14 through 50 which a pin 41 is adapted to be driven at right angles to the plane passing through the axes of both the screw shaft 18 and the guide member 13, the latter serving to hold said jaw against rotation or oscillation on 55 the axis of said head 35 and ball 36 thereby maintaining the face of the jaw 14 opposing the jaw 1 parallel with the opposing face of the latter. Said pin 41 may, however, be removed when desired thereby 60 permitting to the jaw 14 limited pivotal movement on the vertical axis of said head 35 and ball 36 so that it may accommodate itself to work having contact points or faces disposed in non-parallel vertical planes. The head 35 of the said mem- 65 ber 13 is preferably produced by inserting one end of said member 13 into a mold for casting said head 35, said member 13 being provided with a plurality of lateral openings or perforations through which the metal forming said head 35 is made to flow, as shown in Fig. 7, said head being thus firmly secured to said member 13 as will be obvious.
- The vise thus constructed is capable of being very rapidly adjusted to accommodate work varying greatly in width. Its construction is simple and durable and is easily repaired as will be apparent.
- By means of this arrangement the full burden of the pressure exerted on an object engaged between the vise jaws is thrown on the ball and socket joint axially of the screw shaft, regardless of the relative positions of the said jaws, the thrust being transmitted by the screw shaft to the jaws at a point much nearer to their engaging faces than is possible with swivel jaw vises having the screw shaft housed by the guide member carrying the movable jaw.
- I claim as my invention:
1. In a vise, a member adapted to be rigidly mounted upon a support, a member movable relatively thereto, a screw-shaft for imparting movement to the latter relatively to the former, a member pivotally engaged with said rigid member and provided with an opening for the passage of said screw-shaft, portions at opposite sides and ends of said member threaded on their inner faces to engage the threads of said screw-shaft, a sleeve on said screw-shaft longitudinally and rotatably movable relatively thereto, a member carried by said sleeve yieldingly engaging said screw-shaft to cause said member to rotate therewith, means carried by said sleeve operatively engaging said member to impart pivotal movement thereto in opposite directions in accordance with the direction of rotation of the said screw-shaft to throw the threaded portions of said member into and out of engaging relation to said screw-shaft, and stops for limiting the movement of said sleeve longitudinally and rotatably relatively to the said member.
  2. In a vise, a member adapted to be rigidly mounted upon a support, a member movable relatively thereto, a screw-shaft for imparting movement to the latter relatively to the former, a member pivotally engaged with said rigid member and provided with an opening for the passage of said screw-shaft, portions at opposite sides and ends of said member and threaded on their inner faces to engage the threads of said screw-shaft, a sleeve on said screw-shaft longitudinally and rotatably movable relatively thereto, a member carried by said sleeve yieldingly engaging said screw-shaft to

- cause said member to rotate therewith, a segmental flange carried by said sleeve parallel with its axis and having its opposite ends disposed at relatively different distances from said axis, and projections on said member between which said flange is received and engaged, said flange being adapted by rotation of said sleeve by said screw-shaft in respectively opposite directions to impart pivotal movement to said member in respectively opposite directions to throw said threaded portions thereof into and out of engaging relation respectively to said screw-shaft.
- 15 3. In a vise, a member adapted to be rigidly mounted upon a support, a member movable relatively thereto, a screw-shaft for imparting movement to the latter relatively to the former, a member pivotally engaged with said rigid member and provided with an opening for the passage of said screw-shaft, portions at opposite sides and ends of said member and threaded on their inner faces to engage the threads of said screw-shaft, a sleeve on said screw-shaft longitudinally and rotatably movable relatively thereto, a member carried by said sleeve yieldingly engaging said screw-shaft to cause said member to rotate therewith, a segmental flange carried by said sleeve parallel with its axis and having its opposite ends disposed at relatively different distances from said axis, and projections on said member between which said flange is received and engaged, said flange being adapted by rotation of said sleeve by said screw-shaft in respectively opposite directions to impart pivotal movement to said member in respectively opposite directions to throw said threaded portions thereof into and out of engaging relation respectively to said screw-shaft, and projections at the respective ends of said flange adapted to engage at least one of said projections of said member to limit the rotation of said sleeve relatively thereto.
- 40 4. In a vise, a member carrying the rigid jaw adapted to be secured to a support, a box forming an integral part of said member having a removable side wall, a screw-shaft passing through openings in the end walls of said box, a sleeve equipped with
- 5 5. In a vise, a member adapted to be rigidly mounted upon a support, a member movable relatively thereto, a screw-shaft for imparting movement to the latter relatively to the former, a member pivotally engaged with said rigid member and provided with an opening for the passage of said screw-shaft, portions at opposite sides and ends of said member and threaded on their inner faces to engage the threads of said screw-shaft, a sleeve on said screw-shaft longitudinally and rotatably movable relatively thereto, a member carried by said sleeve yieldingly engaging said screw-shaft to cause said member to rotate therewith, a segmental flange carried by said sleeve parallel with its axis and having its opposite ends disposed at relatively different distances from said axis, and projections on said member between which said flange is received and engaged, said flange being adapted by rotation of said sleeve by said screw-shaft in respectively opposite directions to impart pivotal movement to said member in respectively opposite directions to throw said threaded portions thereof into and out of engaging relation respectively to said screw-shaft, and projections at the respective ends of said flange adapted to engage at least one of said projections of said member to limit the rotation of said sleeve relatively thereto.
- 10 6. In a vise, the combination with a fixed jaw member, of a guide member slidably 80 therein, a movable jaw carried by the guide member, a screw shaft for imparting movement to the movable jaw and its carrying member relatively to the fixed jaw member; and a universal joint connection between 85 said screw shaft and said movable jaw, the said joint including means whereby said movable jaw and said screw shaft are immovable relatively to each other in a direction of the axis of the latter; the movable 90 jaw being carried by the guide member upon a pivot at right angles to the plane passing through the axes of both the screw shaft and the guide member, and being immovable with respect to the guide member in a direction transverse to the axis of the said pivot.
- 15 7. In testimony whereof I have signed my name in presence of two subscribing witnesses.
